UNITED STATES PATENT OFFICE.

WILLIAM TUCKER, OF EAST TOLEDO, OHIO.

CAR-COUPING.

SPECIFICATION forming part of Letters Patent No. 228,956, dated June 15, 1880.

Application filed April 16, 1880. (No model.)

To all whom it may concern:

Be it known that I, WILLIAM TUCKER, of 5
East Toledo, in the county of Lucas and State
of Ohio, have invented a new and Improved
Car-Coupling; and I do hereby declare that
the following is a full, clear, and exact description
of the same.

My invention relates to an improvement in
the class of automatic couplings for railroad-
10 cars in which a spring-jaw upon the draw-
head of one car engages with a jaw secured to
the draw-head of the next adjoining car when
the cars are to be coupled, and in which chains
secured to the spring-jaw are employed to draw
15 and hold the spring-jaw in such position that
it will not engage with the jaw of the next ad-
joining car, so that the coupling may be ren-
dered inoperative when desired, or may be
readily uncoupled without going between the
20 cars.

The coupling herein described is more par-
ticularly adapted to freight-cars, although a
portion of the device may be employed upon
passenger-cars by using other mechanism than
25 that herein shown for uncoupling the cars or
for rendering the coupling inoperative.

My invention consists in the combination
and arrangement of parts, as hereinafter shown,
described, and claimed.

30 In the accompanying drawings, Figure 1 is
a plan view of my improved coupling, show-
ing a gondola-car coupled to a box-car, the
spring-hooks of which are shown by full lines
35 in their locked position and by dotted lines
in an unlocked position, and in which is also
shown, in dotted lines, the ordinary link for
coupling the draw-heads in the usual manner
when the hook-coupling is not employed. Fig.
40 2 is a side elevation of Fig. 1, and Fig. 3 a per-
spective view of one of the spring-hooks de-
tached.

The coupling-box or draw-head A may be
secured to the framing of the car B and to the
end of the draw-bar in the usual way, and the
45 general form of the well-known coupling-box
need not be changed except upon its sides. By
this means the ordinary link and pin may be
used to connect the improved coupling with
the common coupling when desired.

50 The improved coupling-box is provided with
a fixed jaw, A', cast upon one of its sides, and

laterally-projecting ears A² A³, cast upon its
opposite side. A spring-jaw, C, having a fan-
shaped jaw, c', at one end and a rectangular
shank, c², at the other, neatly fits between the
ears A² A³, and is pivoted thereto by a pin, c,
that passes through both of the ears and
through the middle portion of the spring-jaw.
The shank c² of the spring-jaw C is located
nearly parallel to the adjacent side of the coup-
ling-box, and is reduced in size at its end to
allow sufficient space between the shank and
the side of the coupling-box to arrange a coiled
spring, D, one end of which is secured to the
jaw-shank c' and the other end of which is se-
cured to the side of the coupling-box, so that
the shank end of the jaw is constantly pressed
away from the coupling-box, to which it is piv-
oted, and the opposite end or jaw is forced in
toward the side of the coupling-box of the next
car, so that when a fixed jaw is formed upon
the adjoining coupling-box the spring-jaw will
interlock with it.

When both adjoining cars are provided with
my improved coupling a double connection is
75 made between the cars, so that if one should
become inoperative by the breaking of a pin
or spring the other jaw will securely couple
the cars together until the defect can be re-
80 medied.

A great advantage of the double spring-hook
connection is that the coupling may be used
upon narrow-gage mountain roads, which em-
ploy curves of such short radius that a single-
hooked connection would become easily dis-
85 connected, and the uncoupled car would be al-
lowed to descend a grade over which it may
be drawn with great danger, or be accidentally
left upon a level grade at night, which would
be attended with great danger.

90 The fan-shaped or flaring end of the spring-
jaw C will not only admit of a firm connection
between the jaws, but will accommodate the
hinged jaw of one car to the fixed jaw of an-
other car of a different height. This is a most
95 important feature in connection with freight-
cars, as gondola-cars or heavy-burden cars are
much lower than box-cars, and in making up a
train cars of different kinds are often coupled
together, especially upon small roads.

100 The rear end or shank, c², of the spring-jaw
is connected upon its inner side with two

chains, E F, one of which, E, passes directly to the opposite side of the car, and, passing through an eye, e , is provided with a ring, e' , upon its end, which, when drawn with sufficient force, may be hitched over a pin, e^2 , secured to a convenient part of the outer side of the car-body, which action will compress the spiral spring and render the spring-jaw inoperative. The chain F is first passed to the same side of the car as the chain E, so as to be parallel with it, and is then carried around a friction-roller, G, and returned to the opposite side of the car, and passes through an eye, f , and is provided with a ring, f' , which may be hooked over a pin, so that the chain F may be used from the other side of the car to operate the spring-hook. By this simple means the spring-hook may be readily operated by simple, cheap, and effectual means from either side of the car.

When the coupling is used upon a box-car the outer ends of the chains E F may be connected to a strap, F', that is held vertically against the side of the car, and is provided at its upper end with a handle, so that the brake-

man may reach it from the top of the car to operate the hooks to uncouple them.

I am aware that a crank-rod and chain have been employed to operate the pivoted laterally-swinging hook or jaw of a car-coupling. I neither claim nor employ such combination of parts.

What I claim as new is—

The combination, with the coupling hook jaw having the fan-shaped part e' and the shank e^2 , which is extended in rear of its pivot and the spring D, arranged as specified, of the chains E and F, which are attached to said shank and arranged as shown—that is to say, one of them passing through an eye, e , at the side of the car and the other passing around contiguous pulley G, and thence through an eye, f , at the opposite side of the car—as shown and described, whereby the coupling jaw may be easily operated by tension on either chain, as set forth.

WILLIAM TUCKER.
